Primary Examiner — Daniel J Domino

(57) **CLAIM**

The ornamental design for an electronic device display screen with animated graphical user interface, as shown and described.

DESCRIPTION

The patent or application file contains at least one drawing executed in color. Copies of this patent or patent application publication with color drawing(s) will be provided by the Office upon request and payment of the necessary fee.

10. **Electronic Device Display Screen With Animated Graphical User Interface**

10.1: Front

10.2: Front

10.3: Front

10.4: Front

10.5: Front

The broken lines in the reproductions form no part of the claimed designs; the appearance of the animated graphical user interfaces sequentially transitions between the images shown in reproductions 10.1 to 10.5, respectively; the process or period in which an image transitions to another image forms no part of the claimed designs.
